(57) **CLAIM**

The ornamental design for a multi-step oval rosette mounting bracket and post, as shown and described.

DESCRIPTION

FIG. 1 is a perspective view of a multi-step oval rosette mounting bracket and post showing my new design;

FIG. 2 is a front view thereof;

FIG. 3 is a right side view thereof;

FIG. 4 is a bottom view thereof;

FIG. 5 is a backside view thereof; and,

FIG. 6 is a left side view thereof.

The broken lines, which define the bounds of the invention, form no part thereof.
